UNITED STATES PATENT OFFICE.

ELMER V. SANTEE, OF WATERTOWN, NEW YORK.

DESIGN FOR A DISPLAY-RACK.

SPECIFICATION forming part of Design No. 24,853, dated November 5, 1895.

Application filed September 30, 1895. Serial No. 564,213. Term of patent 7 years.

To all whom it may concern:

Be it known that I, ELMER V. SANTEE, a citizen of the United States, residing at Watertown, in the county of Jefferson and State of New York, have invented a new and original Design for Umbrella Display-Racks, of which the following is a specification.

This invention relates to a new and original design for umbrella display-racks; and it has for its object to provide a design of this character that shall be both useful and ornamental.

The leading feature of the design resides in a display-rack having an upright series of horizontal parallel pairs of different-sized concentric rectangular figures, the concentric rectangular figures of each pair lying in the same horizontal plane, and the smaller rectangular figure of each pair being provided in its upper side with a continuous depression of a V shape in cross-section, and short radial lines connecting the parallel sides of the rectangular figures of each pair at their centers.

In the drawings, Figure 1 is a perspective view of a complete umbrella display-rack embodying the herein-described design. Fig. 2 is a plan view of one of the racks proper. Fig.

3 is a sectional view of the design illustrated in Fig. 2.

Referring to the drawings, the numeral 1 designates an upright, on which is arranged a series of spaced horizontal racks 2. Each of the racks 2 essentially comprises a pair of different-sized concentric rectangular figures 3 and 4, respectively, which lie in substantially the same horizontal plane. The inner smaller rectangular figure 4 is provided in its upper side with a continuous depression 5 of a V shape in cross-section, and the parallel sides of the figures 3 and 4 are connected at 40 their centers by short radial lines 6, which complete the main design forming the subject-matter of the present invention.

What I claim is—

The design for an umbrella display rack 45 herein shown and described.

In testimony that I claim the foregoing as my own I have hereto affixed my signature in the presence of two witnesses.

ELMER V. SANTEE.
